Inventor:

SECTION E E Joseph Becker,
F.R.C. Munday, Clarke & Clevenger Attorneys

UNITED STATES PATENT OFFICE

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKING RETORT OVEN

Application filed May 16, 1921, Serial No. 470,197. Renewed January 24, 1930.

This invention comprehends improvements of especial utility in the coking retort oven art. The invention has for objects to provide the well-known Koppers cross-wise reversal principle in a crosswise coking retort oven having a double series of horizontal flame flues in each heating wall, the application of the aforesaid reversal principle being preferably combined with reversal of combustion in the double series of horizontal heating flues. The invention further provides for the optional utilization of the gas oven principle, in such a cross regenerative oven, whereby the heat for coking the charges of coal in the regenerators or coking chambers may be developed from the combustion of an extraneously derived special generator gas, such as producer gas, with conservation of the entire product of the relatively richer coke oven gas derived from the coal carbonization process carried on in the retort chambers.

In addition to the general objects recited above, the invention has for further objects such other improvements or advantages in construction and operation as may be found to obtain in the structures and devices hereinafter described or claimed.

In the accompanying drawings, forming a part of this specification and showing, for purposes of exemplification, a preferred form and manner in which the invention may be embodied and practiced, but without limiting the claimed invention specifically to such illustrative instance or instances:

Figure 1 is a crosswise vertical sectional elevation through a coke oven battery embodying features above specified and equipped with the improvements of the present invention, the view being taken longitudinally through a heating wall and a regenerator, in planes indicated by the line A—A of Fig. 2;

Fig. 2 is a composite vertical sectional elevation taken longitudinally of the coke oven battery, in planes indicated by the lines C—C, D—D and E—E of Fig. 1; and

Fig. 3 is a fragmentary detailed horizontal sectional view of a heating wall taken on the line B—B of Fig. 2.

The same characters of reference designate the same parts in each of the several views of the drawings.

In the embodiment illustrated in the drawings, the invention is incorporated in a combination coke-oven battery, i. e.,—a battery having provision for being operated either with an extraneously derived special generator gas, such as producer gas, or with the coke oven gas derived from the distillation of the coal in the coking chambers or retorts of the battery. For convenience, the present description will be confined to the present illustrated embodiment of the invention in such a combination coke oven battery; the novel features and improvements of the invention are capable of other applications, such, for example, as in ordinary so-called "gas ovens" employing producer gas as the fuel, or in ordinary so-called "coke ovens" employing coke-oven gas as the fuel; hence the scope of the invention is not confined to the specific use and specific embodiment herein described as an illustrative example.

Referring to the drawings, there are illustrated views of a coke oven battery or plant of the by-product type, having features above specified; said oven battery embodies in its construction a plurality of crosswise elongated heating walls 11, 11, and a plurality of intermediate crosswise elongated vertical coking chambers 12, 12. The heating walls 11 form the side walls of the respective coking chambers 12, as shown more particularly in Fig. 2, and together with the coking chambers are supported by the heavy supporting walls 13, 13 which extend crosswise of the battery and are located, as shown in Fig. 2, below the superstructure of the battery. The supporting walls 13 collectively form the main support for the entire superstructure of the oven battery and are themselves supported upon a flat mat or platform which constitutes the sub-foundation on which the entire battery rests.

The coal to be coked is charged into the several coking chambers or ovens through charging holes 14 located in the top 15 of the oven battery, and positioned, as shown in Fig. 2, directly above the ovens or chambers 12. These

charging holes 14 are equipped with the usual removable covers, which are removed during charging of the individual ovens or coking chambers and are placed in position to close the tops of such coking chambers during the entire coking or distilling operation. The gases of distillation pass from the tops of the several coking chambers 12 through gas outlets indicated by dotted lines at 16 in Fig. 1, and thence through ascension pipes (not shown) into the usual gas collecting main, which carries the distillation products to the by-product recovery apparatus.

Heating for coking the charges of coal in the several ovens or chambers 12 is derived from the heating walls 11, which, as before mentioned, extend crosswise of the battery at the sides of the coking chambers. As shown, each heating wall is constituted of two parallel series G and H of individual horizontal flame or combustion flues 17, the flues of each series extending parallel with the longitudinal axis of the heating wall. All the flame flues of both series of heating walls, in accordance with the present embodiment of the invention, operate concurrently as burning flues and combustion is maintained concurrently in the flues in all of the heating walls of the battery.

The crosswise regenerators 18 of the retort oven or battery are located below the aforesaid heating walls 11 and coking chambers 12, and in the present instance extend in parallelism between the supporting walls 13. Located in the middle lengthwise vertical plane of the coke oven battery, is a vertical partition 19, as shown in Fig. 1, which partition extends all the way up from the mat of the battery to the bottom of the overlying structure and from one to the other of the pillar walls 13. The regenerators which are respectively located on opposite sides of the battery extend inwardly to said partition 19 and are separated thereby as clearly shown in Fig. 1. This arrangement permits control from opposite sides of the battery of the flow through the regenerators. Each regenerator 18 is a chamber containing open brickwork, commonly called checkerwork, and indicated at 20 with a distributing sole channel 21 underneath such checkerwork, the channels forming the soles of such chambers and opening up into the checkerwork.

The regenerators are heated, in alternation, by the hot combustion products that draw off from the flame or combustion flues hereinbefore mentioned and then impart such heat to the medium that they feed to these flame flues; in the present instance, the series of regenerators 18 on each side of the central partition 19 are disposed, taken seriatim longitudinally of the battery, in groups K, each said group comprising three regenerators and, as shown in Fig. 2, flow is maintained concurrently in the same direction in all the

regenerators of the several groups on one side of the central partition 19, while flow is maintained concurrently in the opposite direction in the several groups of regenerators on the other side of the aforesaid central partition. That is to say, the several groups of regenerators on one side of the partition 19 operate concurrently as inflow regenerators, while the several groups of regenerators on the other side of said partition are operating concurrently as outflow regenerators, this being a common practice, as set forth in the well-known Koppers cross-regenerative Patent No. 818,083, dated April 17, 1906. On reversal of the battery by means of any preferred type of reversing mechanism, the several groups of regenerators which heretofore operated as outflow regenerators become inflow regenerators and concurrently the several groups of regenerators that heretofore operated as inflow regenerators become outflow regenerators.

Located at the opposite ends of each heating wall are groups of vertical feed channels 22 and 23, the feed channels 22 and 23 corresponding to the several groups of regenerators on the opposite sides of the aforesaid partition 19, and each channel preferably having an inner vertical wall 24 and an outer wall 25 which inclines upwardly toward the aforesaid vertical wall 24, as shown in Fig. 1. With this construction, there is a group of three channels at each end of each heating wall, the middle channel P' of the groups 22 on one side of the aforesaid partition 19 being respectively connected with the ends of the several flues 17 of both series G and H by means of ports 26, and the middle channels P' of the groups 23 on the opposite side of the partition 19 being similarly connected with the opposite ends of both series of their corresponding flues by means of similar ports. The end channels A' of the groups 22 on one side of the aforesaid partition 19 are respectively connected with the ends of the several flues 17 of both series by means of ports 27, and the end channels A' of the groups 23 on the opposite side of the partition 19 are similarly connected with their corresponding flues by means of similar ports. This arrangement provides ports connecting respectively the opposite ends of both series of flues of each heating wall with groups of three channels corresponding to the groups of regenerators and positioned at the opposite end of such flues.

When burning an extraneously derived fuel gas, such as producer gas, in the flues 17 each inflow group of regenerators is composed of a middle gas regenerator P for heating the fuel gas and two side air regenerators A for heating the air which enters the flues to support combustion of the gas. All of the outflow groups of regenerators operate concurrently as waste gas regenerators and are des-

gnated by the reference character W. The gas regenerators P of each group, whether operating for inflow or for outflow, are respectively communicably connected by ducts 28 with the middle feed channel P' of the groups 22 or 23; the air regenerators A, whether operating for inflow or for outflow, are respectively communicably connected, by means of ducts 29, with the side feed channels A' of the groups 22 or 23. With this construction, the flame flues of both series of each heating wall are communicably connected on one side of the battery with gas and air regenerators and on the other side of the battery with waste gas regenerators, the latter becoming, on reversal, gas and air regenerators and the former becoming waste gas regenerators.

The reversal in operation of the several flame flues 17 of both groups G and H of the heating walls involves a reversal in direction of flow of the gases through said flues, and a change of the points of supply from one end of both series of such flues to the other, with the result that all of the flues of the entire battery may operate concurrently as burning flues, notwithstanding reversal in flow through the regenerators. The function of such construction is as follows:—The regenerators that prior to the reversal operated as inflow regenerators become outflow regenerators, and the outflow operating regenerators become inflow operating regenerators; the supply of gas from one side of the battery to all of the flues is turned off; and the supply of gas from the other side of the battery to all of the flues is turned on.

Extending from the opposite side walls of the battery and leading into the several feed channels 22 and 23 on both sides of the battery are gas supply ducts 30 and 31. These gas supply ducts 30 and 31 are for the purpose of optionally supplying coke oven gas to the several flame flues of each heating wall. The supply of coke oven gas to the respective ducts 30 and 31 is derived from coke oven gas mains of the usual type that are respectively located on the opposite sides of the battery. Suitable means is provided for admitting or shutting off the supply of gas with respect to the ducts 30 and 31 it being understood that the gas supply, when the oven is operating with coke oven gas, is turned on concurrently either to the series of ducts 30, or to the series of ducts 31.

For operating the battery alternatively for the use of a special generator gas, such as producer gas as a fuel, the several inflow operating regenerators P may be optionally connected with a producer gas main, so that the producer gas may be directed into such of the regenerators as are operating for inflow and conveyed through these regenerators into both groups G and H of the burning flame flues 17. The operation of the retort

oven or battery when using an especial generator gas, such as ordinary producer gas as fuel, is as follows:—The supply of coke oven gas to the coke oven gas main and to all of the coke oven gas ducts 30 and 31 is cut off. A supply of producer gas is permitted to flow into the inflow operating gas regenerators P, and passing through said regenerators is preheated before being delivered into the burning flame flues. During the inflow of producer gas through said regenerators P, waste gas from the other end of the flues is flowing out through all of the regenerators W, on the other side of the partition 19. In the regenerators A, inflow of air is maintained and, passing upwardly through said regenerators, is preheated and finally enters the burning flame flues to support the combustion of the producer gas that is delivered thereto by the regenerators P. On reversal of the flow, the inflow gas and air regenerators become outflow regenerators and concurrently the outflow operating gas regenerators become inflow gas and air regenerators.

In operating the battery with coke oven gas, the supply of producer gas to the regenerators P is shut off and air is permitted to flow into said regenerators in place of the producer gas. During coke oven gas operation, the supply of coke oven gas is maintained in the channels 30 or 31 which feed that end of the burning flues that are in connection with the air regenerators. The reversing mechanism is operated on each reversal to place all of the inflow operating regenerators in communication with the outer air and all of the outflow operating regenerators in communication with the waste gas tunnel.

Alternatively, during such coke oven gas operation, some of the regenerators, such as the regenerators P may be employed for conveying to the flues A neutral gaseous diluent, such as return waste gas, to lengthen the flames in the flues, in the manner and for the purpose set forth in my prior Letters Patent No. 1,416,322, dated May 16, 1922.

The invention as hereinabove set forth is embodied in a particular form of construction but may be variously embodied within the scope of the claims hereinafter made.

I claim:

1. In a coking retort oven, in combination: a plurality of coking chambers; heating walls contiguous to such coking chambers and respectively constituted of two series of horizontal combustion flues; reversible cross-wise extending regenerators parallel with the coking chambers and the heating walls, such regenerators being disposed into two series located respectively on opposite sides of the battery, one series operating for inflow while the other series operates for outflow, the regenerators of each series being disposed into groups of three regenerators with one inflow

120

operating regenerator of each group supplying gas and the others supplying air, the gas regenerator lying between the respective air regenerators; and duct means connecting the groups of such regenerators of each series respectively with the opposite ends of both series of horizontal combustion flues of said heating walls; substantially as specified.

2. In a coking retort oven, in combination: a plurality of coking chambers; heating walls contiguous to such coking chambers and respectively constituted of two series of horizontal combustion flues; reversible crosswise extending regenerators parallel with the coking chambers and the heating walls, said regenerators being communicably connected in groups respectively with the opposite ends of the combustion flues of single heating walls; and means for rendering the groups of said regenerators operable during the inflow period to convey to said flues air and an extraneously derived gas, such as producer gas; substantially as specified.

3. In a coking retort oven, in combination: a plurality of coking chambers; heating walls contiguous to such coking chambers and respectively constituted of two series of horizontal combustion flues; and reversible crosswise extending regenerators parallel with the coking chambers and the heating walls, said regenerators being communicably connected in groups respectively by ducts in substantially straight and unbroken lines with the opposite ends of the combustion flues of single heating walls; substantially as specified.

4. In a coking retort oven, in combination: a plurality of coking chambers; heating walls contiguous to such coking chambers and respectively constituted of two series of horizontal combustion flues; combined with inflow and outflow crosswise regenerators respectively disposed in groups along opposite sides of the coking retort oven, the regenerators of the inflow groups being respectively communicably connected with one end of the combustion flues of single heating walls and being jointly operable for conveying air to the flues or separately operable for conveying the said flues air or an extraneously derived gas, and the outflow groups of regenerators being respectively communicably connected with the opposite ends of the combustion flues of single heating walls; and means for supplying, at will, to said flues an alternative fuel gas, such as coke oven gas; substantially as specified.

5. In a coking retort oven, in combination: a plurality of coking chambers; heating walls contiguous to such coking chambers and respectively constituted of two series of horizontal combustion flues; combined with inflow and outflow regenerators disposed in groups which are respectively communicably connected by ducts in substantially straight and unbroken lines with the opposite ends of

both series of combustion flues of the heating walls, the regenerators of the inflow groups being jointly operable for conveying air to the flues or separately operable for conveying to said flues air or an extraneously derived gas; and means for supplying, at will, to said flues an alternative fuel gas, such as coke oven gas; substantially as specified.

6. In a coking retort oven, in combination: a plurality of coking chambers; heating walls contiguous to such coking chambers and respectively constituted of two series of horizontal combustion flues; combined with inflow and outflow crosswise regenerators disposed in groups which are respectively communicably connected with the opposite ends of the flues of the heating walls, the regenerators of the inflow groups being separately operable for conveying to the said flues air and extraneously derived gas, such as producer gas; substantially as specified.

7. In a coking retort oven, in combination: a plurality of coking chambers; heating walls contiguous to such coking chambers and respectively constituted of two series of horizontal combustion flues; combined with inflow and outflow regenerators disposed in groups which are respectively communicably connected by ducts in substantially straight and unbroken lines with the opposite ends of the flues of the heating walls, the regenerators of the inflow groups being separately operable for conveying to the said flues air and an extraneously derived gas, such as producer gas; substantially as specified.

8. In a coking retort oven, in combination: a plurality of coking chambers; heating walls contiguous to such coking chambers and respectively constituted of two series of horizontal combustion flues; combined with inflow and outflow regenerators having communications with the opposite ends of the flues of the heating walls respectively, each of said communications consisting of a substantially straight duct; substantially as specified.

9. In a coking retort oven, in combination: a plurality of coking chambers; heating walls contiguous to such coking chambers and respectively constituted of two series of horizontal combustion flues; combined with a regenerative system embodying fuel gas and air regenerators communicably connected by ducts in substantially straight and unbroken lines with one end of the flues of the heating walls and waste gas regenerators communicably connected by ducts in substantially straight and unbroken lines with the other end of the flues of the heating walls; substantially as specified.

10. In a coke oven provided with parallel coking chambers, heating walls contiguous to such coking chambers and respectively constituted of a plurality of series of horizontal

combustion flues through which the direction of combustion may be periodically reversed, and regenerators arranged below and having communications with the opposite ends of the flues of said heating walls, each of said communications consisting of a substantially straight duct; substantially as specified.

11. A coke oven provided with parallel coking chambers, heating walls contiguous to such coking chambers and respectively constituted of a plurality of series of horizontal combustion flues through which the direction of combustion may be periodically reversed, fuel gas and air regenerators arranged below and having communications with one end of the flues of said heating walls, and waste gas regenerators arranged below and communicating by ducts in substantially straight and unbroken lines with the opposite end of the flues of said regenerators; substantially as specified.

JOSEPH BECKER.
